APPARATUS FOR DISPENSING STAMPS

Garth Close, Lubbock, Tex.

Application December 26, 1956, Serial No. 630,701

7 Claims. (Cl. 164—43)

The present invention relates to a device for facilitating the distribution of stamps stored in roll form and is particularly useful for distributing trade stamps issued by merchants in proportion to the amount of a sales transaction.

It has been the practice with some merchants over the years to deliver, with purchases of merchandise, stamps which are refundable for items of value. Such trade stamps are usually in sheet form and are stored in juxtaposed or superimposed relationship adjacent the cash register. The clerk after making a sale then computes the number of stamps to which the customer is entitled. It is then necessary to tear the perforated sheets so as to deliver to the customer the proper number of stamps. Such steps are time-consuming and tedious in that the stamps are small and in haste there is often miscalculation of the stamps to which the customer is entitled.

An object of the present invention is to provide apparatus which may be readily manufactured and which is reliable for facilitating the handling of trade stamps and to provide a mechanism wherein the number of stamps to which the customer is entitled may be readily determined to thereby reduce the loss of stamps through miscalculation or carelessness.

A further object of the invention is to provide apparatus for distributing stamps from a supply stored in roll form wherein a given number to be issued is readily determined and to provide the mechanism with means for severing the stamps from the roll by manipulation of the hand which withdraws the stamps from the roll.

Another object of the invention is to provide a mechanism over which the stamps in strip form are arranged and severed by a cutter mechanism which is set in operation by applying pressure to a portion of the apparatus over which the stamps are arranged.

Other objects and features of the invention will be appreciated and become apparent as the present disclosure proceeds and upon consideration of the accompanying drawings and the following detailed description wherein an embodiment of the invention is disclosed.

In the drawings:

Fig. 1 is a perspective view of a device exhibiting the invention and illustrating the manner in which stamps are arranged in position to be cut from the strip.

Fig. 2 is a side elevational view of the apparatus shown in Fig. 1 with portions broken away to illustrate concealed parts.

Fig. 3 is a plan view.

Fig. 4 is an exploded perspective view.

Referring to the drawings there is shown at 10 a base member for the device which may be formed of sheet material such as metal. The base member is desirably of rectangular trough shape as best shown in Fig. 4. A pad 11 may be provided at each of the four corners of the base member and these pads may be of resilient construction whereby the device may be supported on a polished flat surface such as indicated at 12 in Fig. 2.

2

The base is provided along its sides with upstanding flanges 14 and 16. A hole 17 is provided through the flange 16 near the end of the base member as shown in Fig. 4 and this hole is horizontally aligned with a similar hole (not shown) in the flange 14. The base member carries end flanges 18 and 19 which while not being essential serve to join the side flanges 14 and 16 and thus reinforce the structure of the base member.

The apparatus includes a chassis member 20 which is adapted to overlie the base member and is mounted for relative movements with respect thereto as hereinafter described. The chassis member may be formed of sheet material such as metal and provided with a plate portion 21 arranged in a single plane. A flange 22 (Fig. 3) depends from one side of the plate portion 21 and a similar flange 23 extends downwardly from the other side of the plate portion. The transverse distance between the inner faces of the flanges 22 and 23 is greater than the corresponding dimension between the outer surfaces of the flanges 14 and 16 so that the chassis member may overlie the base member in a telescoping relationship.

A housing 25 is carried by the chassis member 20 and it is of arcuate form. The housing may be formed of sheet material and its end walls 26 and 27 are flush with the side flanges 22 and 23. The housing may be formed of separate parts and secured to the chassis member in any desired manner. The housing is provided with a removable lid 28 so that stamps in roll form may be stored within the housing. A depending flange 29 is carried by the chassis member and a portion 30 of the removable lid depends below the plane of the plate portion 21. The flange 29 and the depending portion 30 of the lid are spaced from each other sufficiently to permit lengthwise movement of the chassis member 20 relative to the base member 10 and the purpose thereof will be appreciated as the disclosure proceeds. The chassis member 20 and the housing 25 when in an assembled relation overlie and virtually conceal the base member as shown in Fig. 1.

The free end or leading edge of the stamps in roll form is fed through a slot 31 provided by a portion of the housing 25 adjacent the upper surface of the plate 21 so that the stamps may be withdrawn from the housing to overlie the upper surface of the chassis member 20. A pad 32 formed of yieldable material such as felt is mounted on a plate 33 (Fig. 4) and this plate is supported by resilient straps 34 on the base member 10. The upper surface of the pad is adapted to engage the under surface of the stamps in the vicinity of the slot 31 and thereby serves to prevent the free end portion of the stamps from inadvertently creeping back into the housing and beyond the reach of an operator.

The invention includes means for actuation of a cutter for the stamps withdrawn from the housing 25. Such means includes a cutter bar 36 having a length slightly greater than the transverse dimensions of the plate 21. The knife edge of the cutter bar may be sharpened and serrated if desired. The cutter bar is supported by two arms 37 and 38 each of which is provided with two openings 39 and 41 in ends thereof as shown in Fig. 4. A pin 42 is adapted to extend through the openings 41 in the arms 37 and 38 and through the horizontal aligned openings 17 in the upstanding flanges 14 and 16 of the base member. A similar pin 43 (Fig. 4) extends through the openings 39 in the arms 37 and 38 and through horizontally aligned openings in the depending flanges 22 and 23 of the chassis member. A transverse groove 46 is provided in the upper face of the chassis member for receiving the knife edge of the cutter bar 36. The groove 46 may be filled

with some yieldable material to prevent dulling of the knife edge of the cutter bar when moving thereto in a stamp severing operation.

The invention includes means for actuating the cutter bar 36 and moving it downwardly from the position shown in Fig. 1 when a force is applied to the chassis member 20 so as to move it relative to the base member. The means for shifting the chassis member relative to the base member includes a spring structure shown generally at 50 in Fig. 4. This spring structure may be formed of circular metal stock having resilient characteristics and includes a central portion 51 which is securely anchored to the base member 10 by means of a plurality of clips 52. The intermediate portion of this spring structure remains in fixed relationship with respect to the base. Aligned shaft portions 53 extend in opposite directions from the intermediate portion. These shaft portions are maintained in position by means of bearing brackets 54. A crank arm 56 extends from the free end of each shaft portion 53 and these crank arms terminate in aligned horizontally extending pin portions 57. The pin portions 57 are accommodated in holes 61 in the depending flanges 22 and 23 one of which is shown in Fig. 4.

The top face of the plate portion 21 of the chassis member is provided with index lines to facilitate the determination of the number of stamps the customer is entitled to for a purchase. The stamps are preferably stored in two rolls in the housing 25. One roll may consist of a strip numbering five stamps in width as shown in Fig. 1 while the other roll consists of a strip numbering one stamp in width.

In operation and when it is desired to dispense stamps for a purchase amounting to one dollar and fifty cents the free end of the larger roll of stamps is withdrawn in the direction of the arrow 71 in Fig. 1 until the leading edge is aligned with the transverse line marked 1.50. This may be accomplished by the index finger of the sales person as illustrated in Fig. 1. The rear portion of the palm of the hand is then applied with force to the face of the plate portion 21 so as to urge the associated portion of the chassis member 20 downwardly. The resilient characteristics of the spring structure 50 resists such movement but the outer ends of the shaft portions 53 turn relative to the fixed mid portion of the spring structure. This causes the trunnion or pin portions 57 to swing about the aligned axes of the shaft portions 53. Thus when the chassis member 20 is moved from the position shown in Fig. 2 to a depressed position the chassis member 20 moves downwardly and also moves linearly with respect to the base member 10 and in the direction of the arrow 73 (Fig. 2). Such movement causes the pin 43 to be moved in the direction of the arrow 74 (Fig. 2) and the two arms 37 and 38 pivot about the pin 42 and the cutter bar 36 is moved downwardly and severs the stamps as the knife edge enters the groove 46. The stamps stored in the roll form numbering one stamp in width may be similarly withdrawn from the housing 25 so that the leading edge 76 thereof may be moved until it is aligned with an index graduation in ten cents markings on the plate 21 which may represent a part of the sale price. When the force depressing the chassis 10 is relieved the spring structure 50 returns the chassis member to the elevated position shown in full lines in Fig. 2 when the cutter bar is shifted to the inactive position.

While the invention has been described with reference to the particular assembly it will be appreciated that changes may be made in the elements as well as in the overall organization. Such modifications and others may be made without departing from the spirit and scope of the invention as set forth in the appended claims.

What I claim and desire to secure by Letters Patent is:

1. In apparatus for dispensing stamps, a base member, a chassis member overlying said base member having an

upper surface arranged in a single plane, a housing, means providing a slot adjacent the upper surface of the chassis member through which stamps in sheet form may be withdrawn from the housing to overlie said upper surface, a cutter bar including arms pivotally attached to the base member and pivotally attached to the chassis member, and means for shifting the chassis member longitudinally of the base member upon movement of the chassis member towards the base member to move the cutter bar to a position to sever the stamps.

2. In apparatus for dispensing stamps, a base member, a chassis member overlying said base member having an upper surface arranged in a single plane, a housing carried by the chassis member, means providing a slot between said surface and the housing through which stamps in sheet form may be withdrawn from the housing to overlie said upper surface, a cutter bar including arms pivotally attached to the base member and pivotally attached to the chassis member, and means for moving the chassis member longitudinally of the base member upon movement of the chassis member towards the base member to swing said arms and the cutter bar towards said upper surface.

3. Apparatus for dispensing stamps comprising, a base member, a chassis member overlying said base member, an upper surface on said chassis member arranged in a single plane, a housing for storing a sheet of stamps in roll form, means providing a slot adjacent said upper surface through which said sheet may be withdrawn from the housing to overlie said upper surface, a bar having a cutting edge directed towards said upper surface, arms supporting said bar, a pin pivotally connecting free ends of said arms to said chassis member, a pin connecting free ends of said arms to said base member, and spring means including a crank arm having a trunnion portion pivotally connected to said chassis member and a portion secured to the base member so that upon movement of the chassis member towards the base member the chassis is shifted longitudinally to bodily swing the first pin about the axis of the second pin to move said cutting edge towards said upper surface.

4. Apparatus for dispensing stamps comprising, a base member, a chassis member overlying said base member, an upper surface on said chassis member arranged in a single plane, a housing for storing a sheet of stamps in roll form, means providing a slot adjacent said upper surface through which said sheet may be withdrawn from the housing to overlie said upper surface, a bar having a cutting edge directed towards said upper surface, arms supporting said bar, a pin pivotally connecting free ends of said arms to said chassis member, a pin connecting free ends of said arms to said base member, a spring structure having an intermediate portion secured to said base member, aligned shaft portions extending from said intermediate portion each having resilient characteristics in torsion so that outer ends thereof may be rotated relative to inner portions, an inclined crank arm carried by the outer end of each shaft portion terminating in a pin, and means pivotally connecting each pin to said chassis member.

5. Apparatus for dispensing stamps comprising, a base member of trough shape, a chassis member overlying said base member in telescoping relationship, an upper surface on said chassis member arranged in a single plane, a housing for storing a sheet of stamps in roll form, means providing a slot adjacent said upper surface through which the sheet may be withdrawn from the housing to overlie said upper surface, means releasably holding the sheet in a withdrawn position, a bar having a cutting edge directed towards said upper surface, arms supporting said bar, a pin pivotally connecting free ends of said arms to said chassis member, a pin connecting free ends of said arms to said base member, an inclined crank arm having a trunnion portion pivotally connected to said chassis member, and resilient means secured to said base member re-

sisting swinging movement of said crank arm whereby movement of the chassis member towards the base member bodily swing the first pin about the axis of the second pin to move said cutting edge towards said upper surface.

6. Apparatus for dispensing stamps comprising, a base member of trough shape having upstanding flanges along sides thereof, a chassis member having depending flanges along sides thereof overlying said base member in telescoping relationship, an upper surface on said chassis member arranged in a single plane, a housing for storing a sheet of stamps in roll form which may be withdrawn from the housing to overlie said upper surface, a bar having a cutting edge directed towards said upper surface, arms supporting said bar, a pin pivotally connecting free ends of said arms to said depending flanges, a pin connecting free ends of said arms to said upstanding flanges, a spring structure having an intermediate portion secured to said base member, aligned shaft portions extending from said intermediate portion and having resilient torsional characteristics so that outer ends thereof may be rotated relative to inner portions, a crank arm carried by the outer end of each shaft portion terminating in pins pivotally connected to said depending flanges.

7. Apparatus for dispensing stamps comprising, a base member, a chassis member overlying said base member, 25 an upper surface on said chassis member arranged in a

single plane, a housing for storing a sheet of stamps in roll form, means providing a slot adjacent said upper surface through which said sheet may be withdrawn from the housing to overlie said upper surface, a bar having a cutting edge directed towards said upper surface, arms supporting said bar, a pin pivotally connecting free ends of said arms to said chassis member, a pin connecting free ends of said arms to said base member, spring means including a crank arm having a trunnion portion pivotally connected to said chassis member and a portion secured to the base member so that upon movement of the chassis member towards the base member the chassis is shifted longitudinally to bodily swing the first pin about the axis of the second pin to move said cutting edge towards said upper surface, and said chassis member having a groove for receiving the cutting edge of said bar.
